PUMPING SYSTEM

Filed March 18, 1948

UNITED STATES PATENT OFFICE

2,573,297

PUMPING SYSTEM

Edward B. Atkinson, Steubenville, Ohio, assignor
to National Steel Corporation, a corporation of
Delaware

Application March 18, 1948, Serial No. 15,593

6 Claims. (Cl. 103—40)

1

The present invention relates to improvements in pumping systems for pumping liquid from a lower to a higher elevation, and is primarily concerned with preventing damage to the system and its component parts by surging liquid.

In pumping systems for pumping, for example, water from a source at a relatively low level up to a plant or storage facilities located on a high bank or bluff, a relatively high head or pressure is developed. If the pump is stopped the ram effect of the back or downwardly surging water may cause a damage to the pump and the equipment. It is common practice, in such pumping systems, to use an electrically driven centrifugal pump and when the pump is stopped as a result of power failure or other cause, the water will flow downwardly through the system and operate the pump in reverse. Operating the pump in reverse at high speeds may cause damage to the pump and if the power comes back on with the pump in reverse, the pump may be damaged by the sudden change in direction of operation.

Accordingly, the object of the present invention is to provide an improved pumping system for pumping liquid from a lower to a higher level so constructed and arranged that no damage will result when the pump is stopped.

Another object of the present invention is to provide an improved pumping system for pumping liquid from a lower to a higher level, so constructed and arranged as to prevent harmful flow of liquid downwardly through the system when the pump is stopped.

It is also an object of the present invention to provide an improved pumping system for pumping liquid from a lower to a higher level including control means automatically operable to restrict downward flow of liquid through the system upon the stopping of the pump.

It is also an object of the present invention to provide an improved pumping system for pumping liquid from a lower to a higher level including control means automatically operable to restrict downward flow of liquid through the system upon the stopping of the pump.

In accordance with a preferred embodiment of the present invention, a pumping system which includes a conduit extending from a lower to a higher elevation is provided with a pump, a normally open valve on the inlet or outlet side of the pump, and either mechanical or electrical control means automatically operable to close the valve when the pump stops as a result of power failure or other cause. The valve is in the relatively open position when the pump is

2

operating normally to allow substantially unrestricted flow of liquid upwardly through the conduit. The valve is so constructed and arranged that when it is in a relatively closed position the valve is only partially closed so as to allow restricted flow of liquid through the conduit. Thus, when the pump stops, the control means automatically closes the valve to the partially closed position so that the liquid flows downwardly through the system at a greatly reduced rate of flow. The backward flow is maintained at a sufficiently low rate to prevent damage to the pump when the pump is again started. As the valve is only partially closed, the head or back pressure is gradually dissipated and the backsurge of the liquid is cushioned. If no valves were provided the pump and possibly other portions of the system would be damaged. If the valves were completely closed the ram effect of the backsurging liquid would damage the pumping system.

These and other objects and advantages will become more readily apparent from the following detailed description, taken from the accompanying drawings, in which:

Figure 1 is a schematic representation of a pumping system embodying the principles of the present invention;

Figure 2 is an enlarged view, partially in section, of a valve embodying the principles of the present invention and being part of the pumping system of Figure 1; and

Figure 3 is a diagrammatic representation of a wiring diagram and control means for closing the valve of Figure 2.

Referring more particularly to Figure 1 of the drawings, the pumping system includes a long conduit 10 terminating at its lower end in a pipe 11 which extends below the surface of a body of supply water indicated at 12. The body of supply water 12 may be a river, pond, tank or other source located at a relatively low level. The conduit 10 extends up a relatively steep grade or embankment 13 to a tank indicated at 14. The tank 14, which is at the upper outlet end of the conduit 10, may be a tank of the water system of a mill or may be any other suitable place of disposal which is at a higher elevation than the source at 12. The pumping system includes a centrifugal pump 16 operated by a motor 17 Figure 3, for pumping the liquid from the source 12 to the tank 14.

A power actuated valve 18 is provided in the conduit 10 for controlling the flow of liquid through the system. This power actuated valve

18 is shown more fully in Figure 2. The valve means 18 includes a valve casing 19, having a circular substantially disc-like, relatively thinner valve member 20 extending across the passage 21 in casing 19. The passage 21 is in communication with other portions of the passage through the conduit 10. The valve member 20 is mounted on and connected to a shaft 22 rotatably mounted in the casing for rotation about its axis.

The axis of rotation of shaft 22 and valve member 20 extends transversely of passage 21 and parallel both to a diameter of the circular passage 21 and a diameter of the circular valve member 20. Glands 23 and 24 are provided for sealing the valve and preventing leakage of liquid. The shaft 22 extends outside of the casing 19 and also is suitably rotatably mounted in the framework 25. Motor 26 is connected through shaft 27 and suitable gearing inside the gear cover 28 to the shaft 22 so that as the motor 26 is rotated the shaft 22 is turned to open or close the valve. A suitable, releasable brake 30 is provided for automatically engaging drum 31 on shaft 22 to hold the valve member 20 in a fixed open or closed position. The brake 30 may be of any suitable type and preferably is automatically released upon energization of motor 26 to permit the motor to turn the shaft 22 and valve member 20 as desired. The motor 26 may be reversible or may rotate in the same direction to move the valve member 20 to the relatively open and closed positions.

The circular valve member 20 is shown in Figure 2 in the closed position. The thickness of member 20 is considerably less than its diameter so that when the member is turned 90° from the position shown in Figure 2 to the position indicated in Figure 3, the valve is in the open position and permits substantially unrestricted flow of liquid through the conduit 10. Member 20 has a smaller diameter than the passage 21 so that when the valve member is in the relatively closed position there is a relatively small space 32 between the edge of member 20 and passage 21 and liquid can flow through this space at a greatly reduced rate of flow.

Referring more particularly to Figure 3, the pump motor 17 is connected by wires 33 and 34 to wires 35 and 36 which are connected to a suitable source, not shown, of electric current and these wires constitute a simplified circuit for supplying electric current to motor 17. This circuit may include other control means and switches, if desirable. Control means for closing valve 18 upon de-energization of motor 17 is also shown in Figure 3. As diagrammatically shown, the valve motor 26 is connected to a limit switch 33', brake drum 31 and valve member 20 so that these elements rotate in unison. The motor 26 is connected through a wire 34' to one side of a battery 35'. Motor 26 is connected through wire 36', normally closed switch 37, wire 38, contacts 39 and 40, and wire 41 to the other side of battery 35'. With switch 37 closed and switch contacts 39 and 40 closed the motor 26 is energized to rotate the motor in a counterclockwise direction. As the motor rotates, it rotates limit switch 33' and when limit switch 33' has turned 90 degrees, the projection 42 engages switch 37 to open the switch and de-energize the motor 26. Limit switch 33' is so constructed and arranged that switch 37 is opened when valve member 20 is in the closed position shown in Figure 2. A solenoid 44 is connected through wire 45 to wire 34' and through wire 46 to wire 36' so that solenoid 44

is energized and de-energized simultaneously with motor 26. When solenoid 44 is energized it disengages the brake 30 from brake drum 31, so that the motor 26 and the valve member 20 can turn. With solenoid 44 de-energized the brake 30 engages drum 31 to hold the valve member 20 in a fixed position.

A solenoid 48 is connected through wires 49 and 50 to wires 36 and 35 so that when motor 17 is energized or de-energized, solenoid 48 is simultaneously energized or de-energized. Solenoid 48 is connected to switch 51 and when energized, it holds switch 51 open against the action of a tension spring 52. When solenoid 48 is de-energized, spring 52 holds switch 51 closed and contacts 39 and 40 connected.

Normally, the pump 16 and its motor 17 are operated substantially continuously so that switch 51 and valve 18 are normally open. When pump motor 17 is de-energized as a result of power failure, or other cause, current no longer flows through wires 35 and 36 and solenoid 48 is de-energized. With solenoid 48 de-energized, switch 51 closes and solenoid 44 and motor 26 are energized by the battery 35', or other source of power. Energization of solenoid 44 releases brake 30 from drum 31 and the energized motor 26 closes valve 18. When the valve member 20 has been turned 90°, the projection 42 engages switch 37 and opens this switch to de-energize motor 26 and solenoid 44. The brake 30 engages drum 31 and holds the valve member in this relatively closed position.

Any suitable control means may be provided for automatically or manually reopening valve 18 when motor 17 is again energized. Such control means forms no part of the present invention.

When valve 18 is in the relatively closed position the pump motor 17 is not energized, liquid flows downwardly through the space 32 and the pump 16 to operate the pump in reverse at a relatively slow speed. The size of space 32 may vary depending upon various factors but is small enough so that the pump 16 will not be operated in reverse at a sufficiently high speed to cause damage to the pump, especially when the motor 17 is again energized to operate the pump in the forward direction. In one particular installation where water is pumped up 200 feet, it has been found that a $\frac{1}{4}$ inch space around valve member 20 permits sufficient water to flow downwardly to operate the pump 16 in reverse at about 25 revolutions per minute, and at this speed the pump is not damaged when the motor 17 is suddenly energized to rotate in the forward direction. A smaller clearance of, for example, about $\frac{1}{8}$ inch can be used.

The motor 26 takes time to close valve 18 and in the installation mentioned above, the motor requires about five seconds to close valve 18. When the motor 17 is de-energized, the upwardly flowing liquid changes direction and surges downwardly through the conduit. Closing the valve gradually eliminates any objectionable ram effect by the back-surge liquid to prevent damage to the apparatus. As the valve member 20 is being turned to the closed position, water flows downwardly through the valve and this aids in cushioning the back surge of the liquid in the conduit when motor 17 stops. As liquid slowly leaks past the valve, the head of liquid is further dissipated which reduces the torque required to start the pump 16 in the forward direction and this tends to increase the life of the apparatus.

I claim:

1. In a liquid pumping system, a conduit extending from a lower inlet end to an outlet end at a higher elevation, pump means arranged to pump liquid upwardly through the conduit between the pump and the outlet end, valve means associated with the conduit for controlling the flow of liquid through the conduit, said valve means being operable to an open position in which the valve means permits substantially unrestricted flow of liquid through the conduit and being operable to a partially closed position in which valve means permits restricted flow of liquid through the conduit, and control means associated with the pump means and the valve means constructed and arranged to operate the valve to said partially closed position only upon stoppage of the pump means, whereby the valve means permits restricted flow of liquid downwardly through the conduit when the pump stops.

2. In a liquid pumping system, a conduit extending from a lower inlet end to an outlet end at a higher elevation, pump means arranged to pump liquid through the conduit, normally open valve means between the pump means and the outlet end having a valve passage and a movable valve member in the passage for controlling the flow of liquid through the conduit, said valve member being smaller than the valve passage when in the most nearly closed position, and control means associated with the pump means and the valve means operable to effect movement of said valve member from the normally open position to said most nearly closed position only upon stoppage of the pump means whereby the valve means restricts flow of liquid downwardly through the conduit when the pump means stops.

3. In a liquid pumping system, a conduit extending from a lower inlet end to an outlet end at a higher elevation, a pump arranged to pump liquid through the conduit, an electric motor for operating the pump, a normally open, partially closeable valve associated with said conduit between the pump and the outlet end for controlling the flow of liquid through the conduit, power actuated means for operating the valve from the normally open to the partially closed position, and electrically operated control means for the power-actuated means operable only upon de-energization of the pump motor to cause said power actuated means to partially close said valve whereby restricted flow of liquid downwardly through the conduit is permitted upon de-energization of the pump motor.

4. In a liquid pumping system, a conduit extending from a lower inlet end to an outlet end at a higher elevation, a pump for pumping liquid through the conduit, an electric motor for operating the pump, normally open valve means between the pump and the outlet end for controlling the flow of liquid through the conduit including a valve casing having a circular passage extending therethrough and including a circular, relatively thinner valve member in said passage supported for rotation about an axis extending parallel to a diameter of the valve passage and to a diameter of the valve member for movement to relatively open and closed positions, means for rotating the valve member about said axis from the relatively open to the relatively closed position, and control means oper-

able only upon de-energization of said electric motor to actuate the rotating means to move the valve member to the closed position, said valve member having a diameter less than said passage so that there is a clearance space between the periphery of the valve member and the passage wall whereby the valve member permits restricted flow downwardly through the conduit when in the closed position.

5. In a liquid pumping system, a conduit extending from a lower inlet end to an outlet end at a higher elevation, a pump arranged to pump liquid through the conduit, an electric motor for operating the pump, valve means between the pump and the outlet end for controlling the flow of liquid through the conduit including a valve passage, a valve member in the valve passage movable from a substantially open to a flow-restricting position, an electric valve motor for moving the valve member to the flow-restricting position, said valve member being smaller than the valve passage when in the closed position, and an electrical circuit for supplying electric current to the valve motor, said circuit including electrically controlled switch means closeable only upon de-energization of the pump motor, whereby the valve member is moved to the closed position to restrict the flow of liquid downwardly through the conduit and the system when the pump motor is de-energized.

6. In a liquid pumping system, a conduit extending from a lower inlet end to an outlet end at a higher elevation, a pump arranged to pump liquid through the conduit, an electric motor for operating the pump, valve means between the pump and the outlet end for controlling the flow of liquid through the conduit including a valve passage, a valve member in the valve passage movable from an open to a flow-restricting position, and an electric valve motor for moving the valve member to the flow-restricting position, said valve member being smaller than the valve passage, whereby said valve member when in the closed position permits restricted flow through the valve passage and the conduit passage, an electrical circuit for supplying electric current to the pump motor, an electrical circuit including a switch for supplying electric current to the valve motor, and electrically controlled means electrically connected to the pump motor circuit for holding the switch in the open position only when current is flowing to the pump motor so that the valve motor is energized to move the valve member to the flow-restricting position to restrict the flow of liquid downwardly through the conduit and the system only upon de-energization of the pump motor.
